UNITED STATES PATENT OFFICE.

JOSEPH GRUNT, OF CLEVELAND, OHIO.

SAND-HANDLING APPARATUS.

Application filed January 6, 1922. Serial No. 527,491.

To all whom it may concern:

Be it known that I, JOSEPH GRUNT, a citizen of the United States of America, residing at Cleveland, in the county of Cuyahoga and State of Ohio, have invented certain new and useful Improvements in Sand-Handling Apparatus, of which the following is a specification.

This invention relates to certain new and useful improvements in sand handling apparatus for metal foundries and has particular reference to the provision of cooperative devices for scooping sand continuously from a pile and delivering the same to a sifting apparatus so that the sifted sand will be delivered to an elevating conveyor and from thence to delivery chutes associated with spouts through which the material passes for filling sand molds.

An object of the invention is to provide means for continuously scooping the sand from a pile and delivering the same to a sifting apparatus, which means is mounted so as to effectively operate upon a comparatively large pile.

Another object of the invention is to provide a sand handling device for metal foundries of generally simplified and improved construction.

With the above general objects in view and others that will appear as the nature of the invention is better understood, the same consists in the novel form, combination and arrangement of parts hereinafter more fully described in connection with the accompanying drawings, in which like reference characters indicate similar parts throughout the views.

In the drawings.

Figure 1 is a side elevational view of a sand handling device constructed in accordance with the present invention.

Figure 2 is a horizontal sectional view taken substantially upon line II—II of Figure 1.

Figure 3 is a fragmentary vertical sectional view taken substantially upon line III—III of Figure 1.

Figure 4 is a view similar to Figure 3 on line IV—IV of Figure 1.

Figure 5 is a vertical sectional view taken on line V—V of Figure 1.

Figure 6 is a fragmentary substantially central longitudinal sectional view of the

device shown in Figure 1 and drawn on a larger scale.

Figure 7 is an enlarged fragmentary detail view showing the pivotal connection of the inner end of the scooping device with the frame of the sand handling apparatus.

Figure 8 is a fragmentary view partly in section of one of the mold filling spouts and adjacent parts.

Figure 9 is a sectional fragmentary view showing the forward end of the scooping apparatus and illustrating one of the scoops further advanced than illustrated in Figure 6.

Figure 10 is a view similar to Figure 9 with the scoop still further advanced.

Figure 11 is a view similar to Figure 10 with the scoop advanced slightly further than in Figure 10 toward dumping position, and

Figure 12 is a view similar to Figure 11 showing the scoop in dumping position.

Referring more in detail to the several views, the invention preferably embodies a platform 5 having a plurality of uprights 6 near one end thereof which are rigidly connected and mounted so as to form a frame for an upright transversely positioned elevating conveyor which preferably includes a pair of spaced chains 7 which pass around sprocket wheels 8 which are suitably fixed upon a longitudinally arranged power shaft 9 journaled in a horizontal position below the platform 5 as clearly shown in Figure 6 and also around further sprocket wheels 10 fastened upon a longitudinally arranged shaft 11 suitably journaled above the shaft 9 and seen clearly in Figures 1 and 4. The chains 7 pass downwardly into a suitable hopper 12 having a sloping inner wall as clearly shown in Figure 6, and said chains are connected at intervals by means of cross bars 13 to which the heel portions of scoops or buckets 14 are pivoted, each bucket 14 being provided with a pair of upwardly extending hooks 15 arranged to engage an adjacent cross bar 16 which connects the chains 7 near each bucket whereby said buckets are allowed to tilt backwardly when in elevated dumping position as shown in Figure 4 but are prevented from tilting in the opposite direction when operatively disposed to scoop sand from the hopper 12 as shown in Figure 3. Between

- each pair of buckets 14, the chains 7 are connected by a pair of cross bars 17 to which the ends of a plate 18 are attached and each plate 18 carries a rigid obliquely positioned 5 substantially U-shaped scraper member 19 arranged to engage the walls of the hopper 12 so as to keep the sand loose and stack the same centrally in position to be scooped by the buckets 14.
- 10 Means is provided for scooping the sand from the platform 5 and delivering the same to the hopper 12 which embodies a pair of longitudinal frame bars 20 suitably rigidly connected in spaced relation and having 15 rigid uprights 20 and 21 at the ends thereof, the uprights 21 being connected by a transverse board 22 at their upper ends to which is rigidly secured a horizontal plate 23 which projects toward the elevating conveyor 20 above described and is apertured at its free end as at 24 for pivotal reception of a pivot pin 25 which is preferably hook-shaped as shown in Figure 7 and which is rigidly fastened to a longitudinal horizontal beam 25 26 which is suitably supported at the required elevation above the hopper 12 in any manner by the uprights 6. The uprights 20 and 21 carry suitable bearings 27 which are arranged in spaced pairs so as to form bearings 30 respectively for the opposite ends of horizontal transverse shafts 28 and 29. The shafts 28 and 29 each carry a pair of sprocket wheels 30 in such position that each sprocket wheel on the shaft 28 is alined with one sprocket wheel on the shaft 29 and endless sprocket chains 31 pass around these sprocket wheels. The chains 31 are connected at suitable intervals by transverse rods 32, and the legs of a substantially U-shaped member 33 are twisted around the end portions of each rod to swing in a vertical plane with the free end portions of the legs of each member 33 extending at an 35 angle to the remainder of the legs as shown in Figure 6. The central portion of each member 33 is outwardly offset as at 34 and this central portion is engaged at opposite sides of the offset portion 34 by means of bent lugs 35 of a scoop 36 in such manner that the scoop is pivotally mounted for 40 swinging in a vertical plane with the lugs 35 extending upwardly when the bucket is in scooping position and with the offset portion 34 arranged to engage a wall of the scoop 36 for preventing the latter from tilting backwardly beyond a predetermined position wherein it is properly located to scoop material from the platform 5. In 45 order to provide for the easy travel of the chains 31 as well as to prevent sagging of the same, the rods 33 have suitable rollers 37 journaled thereon outwardly of the legs of the members 33 in position to ride upon suitable track bars 38 carried by the frame bars 20 and upper track bars 39 disposed

above the bars 38 and supported by the uprights 20 and 21. The uprights 20 and 21 also support intermediate horizontal bars 40 which are arranged in spaced relation to and above the bars 38 to be engaged by the 70 free end portions of the legs of the members 32 in a manner and for a purpose which will presently become apparent.

The upright 21 at one side of the machine carries a suitable supporting bracket 41 on which is mounted a motor 42 having a pinion 42' fixed to its power shaft in position to mesh with one of a pair of idler pinions 43 which are journaled upon a shaft 44 carried by brackets 45 at each side of the machine that are secured to the inner edges of said uprights 21. The idler pinions 43 mesh with and are disposed above large spur gears 46 secured upon each end portion of the shaft 29, and by means of this motor and gearing, the sprocket wheels 30 are caused to rotate for causing movement of the endless chains 31 and the scoops 36 connected thereto.

At the inner ends of the track bars 38, hook members 47 are provided in positions to have the free end portions of the legs of the members 33 ride thereunder just prior to the time when the scoops pass upwardly at the inner end of the scoop mechanism, so that upon continued movement of the chains 31, the member 33 will be caused to swing about the rod 32 thereof as denoted by the relative positions of the parts in Figures 6 and 9. This causes the scoop to be elevated and then partially lowered to a position directly in front of the rod 32 with the free ends of the legs of the member 32 riding on the under edges of the bars 40 whereby further downward movement of the scoop is prevented. A frame 48 is supported from its upper end as at 49 by the transverse member 22 as shown in Figure 5 and has its lower end curved so as to lie inwardly of and in close proximity to the chains 31. Trip lugs 50 are carried by the frame 48 slightly above the shaft 29 so that upon continued movement of the chains, the lugs 35 of the scoop will engage the same and cause instantaneous tilting of the scoop to the position of Figure 12 whereby the contents of the scoop are dumped. Suitable trip members 51 may be pivoted to the bars 38 so as to be engaged by the rollers 37 in such manner that the latter and the chains 31 may travel in the proper direction but will be prevented from travelling in the opposite direction accidentally or otherwise. By swinging the scooping mechanism about the pivot 25, said mechanism may serve to deliver material from the platform 5 when scattered thereon to the elevating conveyor and said scooping mechanism may be swung out of the way whenever it is desired to place more sand on said platform 5.

An inclined chute 52 is suitably supported between the vertical strands of the chains 7 of the elevating conveyor so that its inner end is highest, and this higher inner end of the chute 52 is provided with a foraminous bottom 53 situated to have the contents of the scoop 26 dumped thereon, while the remaining portion of the bottom of the chute 52 is imperforate. As shown clearly in Figures 1 and 2, the portion of the chute 52 which is provided with the foraminous bottom is enlarged and is provided with a lateral arm 54, the outer end of which is pivotally engaged by another arm 55 fastened to a longitudinally arranged shaft 56 which is suitably journaled in a horizontal position to extend alongside of the elevating conveyor. The portion of the shaft 56 to which the arm 55 is attached is offset to provide a crank 57 and a sprocket wheel 58 is secured upon the other end of said shaft 56 in line with a larger sprocket wheel 59 that is fastened upon the foot shaft 9 of the elevating conveyor, while a chain 60 passes around the sprocket wheels 58 and 59 so that rotary motion of shaft 9 is transmitted to the shaft 56 and through the medium of the crank 57 and arms 54 and 55, the chute 52 is vertically vibrated for causing the finer particles to be sifted through the foraminous bottom 53 onto the inclined wall of the hopper 12 while the larger particles are caused to travel down the chute to its lower end and then from the chute to a desired point of deposit such as in a receptacle properly placed for this purpose. The sand sifted through the foraminous bottom 53 will pass downwardly in position to be engaged by the scrapers 19 and the buckets 14 of the elevating conveyor.

A beam 61 is suitably supported at each side of the beam 26 so that said beams 61 are parallel with the beam 26 and slightly lower whereby oppositely inclined chutes 62 are properly supported by said beams 26 and 61 inwardly of the elevating conveyor so that adjacent higher ends of the chutes 62 are end to end and the chutes extend transversely of the machine as shown in Figure 5. A transverse chute 63 is also supported in an inclined position with its higher end between the strands of the chains 7 of the elevating conveyor directly beneath the head shaft 11 of said conveyor and in position to receive the contents of the buckets 14 as the latter are inverted, and the lower end of the chute 63 is positioned to discharge onto the chutes 62 as shown clearly in Figure 1. The shaft 11 extends inwardly and above the chutes 62 and has a large spur gear 64 fastened upon the inner end thereof which is in mesh with a spur pinion 65 that is fastened upon the power shaft 66 of a motor 67 supported by a suitable bracket 68 carried by a frame plate 69 of the ma-

chine. A crank shaft 70 is supported by the frame plate 69 and another frame plate 71 parallel therewith, and said crank shaft 70 has a pinion 72 upon one end thereof in mesh with the pinion 65. At the opposite side of the gear 64 is another crank shaft 73 journaled in the plates 69 and 71 and having a pinion 74 secured on one end thereof to mesh with the gear 64. Each crank shaft 70 and 73 has a pair of angular arms 75 pivoted thereon in spaced parallel relation with the shorter portions of said angular arms vertical and depending toward the chutes 62 as seen in Figure 5, the longer portions of said arms 75 extending laterally outwardly within the adjacent chute 62 as shown in Figure 1. These longer portions of the angular arms 75 are connected at suitable intervals by transverse vertical plates 76 and the extreme outer end portions of the horizontal members of the arms 75 slidably rest upon a roller 77 journaled on an upstanding frame 78 which is of inverted U-shape and which has the free end portions of its legs outturned to provide pivots upon which the upper end of a filling spout 79 is swingingly mounted. The legs of the frame 78 are also attached to a hinged lower end section 80 of the chute 62 which is normally held raised by means of spring hinges 81. Each filling spout preferably embodies rigid end members of tubular form connected by a tubular flexible intermediate section 82. It will be seen from the foregoing description that the motor 67 serves to operate the arms 75 and the elevating conveyor as well as the sifting chute 52 while the motor 42 operates the scooping device.

In operation, the motors 42 and 67 are placed in operation by any suitable or well known means. The motor 42 causes inward travelling of the lower spans of the chains 31 and as the scoops 36 move therewith the sand is caused to be scooped from the platform 5 and delivered onto the foraminous bottom 53 of the chute 52. The motor 67 causes travelling movement of the chains 7 of the elevating conveyor so that the strands of said chains which are at the right in Figure 3 move downwardly for causing the buckets 14 to engage the sand in the hopper 12 and to elevate said sand above the chute 63, the sand being delivered into the hopper 12 through the foraminous bottom 53 while the larger particles such as stones will travel down the chute 52 and off of the lower end thereof. Just prior to the engagement of each bucket 14 with the sand in the hopper 12, said sand is heaped by a scraper 19 for effectively filling the bucket 14 and when said bucket reaches the upper shaft 11 and then continues to move, it is inverted to deliver its contents onto the chute 63. While this is taking place, the sifting operation is positively carried on by reason of the agita-

tion of the chute 52 through the mechanism above described involving the shaft 56, etc. The sand passes down the chute 63 by gravity onto the chutes 62, some of the sand passing down one chute and some down the other and as the crank shafts 70 and 73 are rotated, the arms 75 are given an orbital movement so as to first move toward the bottoms of the chutes 62, then outwardly so that the sand is separated into desired quantities and moved toward the adjacent filling spout 79. The arms 75 then move upwardly out of engagement with the sand and return to their original position. This cycle of operation is continuous when the machine is operated and by reason thereof predetermined quantities of sand are intermittently delivered to the filling spouts. It will, of course, be understood that the scraper plates 76 are normally inoperative as shown in Figure 5 but that when the end sections 80 are caused to swing downwardly by a downward pull upon the filling spouts, said plates 76 will be allowed to move into engagement with the bottoms of the chute 62. If further downward movement of the plates 76 is desired, the rollers 70 may also be swung downwardly for this purpose. Sand molds may be intimately placed beneath the filling spouts 79 to be filled, and the amount of sand delivered to each filling spout at a time is preferably the quantity desired for one mold.

From the foregoing description, it is believed that the construction and operation of the invention will be readily understood and appreciated by those skilled in the art.

Minor changes may be made without departing from the spirit and scope of the invention as claimed.

What is claimed as new is:

1. In a sand handling machine of the class described, a mold filling spout, means to deliver predetermined quantities of sand to said spout intermittently, sand sifting mechanism beneath said delivering means, means to elevate the sifted sand to said delivering means, and scooping mechanism to deliver unsifted sand to the sifting mechanism.

2. In a sand handling machine of the class described, a mold filling spout, means to deliver predetermined quantities of sand to said spout intermittently, sand sifting mechanism beneath said delivering means, means to elevate the sifted sand to said delivering means, and scooping mechanism to deliver unsifted sand to the sifting mechanism, said scooping mechanism embodying a frame pivoted at one end upon a vertical axis whereby the same may operate upon a pile of sand within a considerable radius.

3. In combination with a mold filling spout and means for intermittently delivering predetermined quantities of sand there-

to, means to elevate sand to said delivering means including an endless conveyor having a plurality of buckets and scraper members alternately with the buckets and formed to stack the sand in the path of said buckets. 70

4. In a sand handling device for metal foundries, a sifting mechanism, and scooping mechanism to deliver unsifted sand to said sifting mechanism, said scooping mechanism comprising a pair of spaced parallel endless chains connected at intervals by transverse rods, substantially U-shaped members having legs with portions extending at an angle to each other and with the intermediate portion of the legs pivotally engaged with said rods whereby the U-shaped members are mounted for vertical swinging movement, scoops pivotally mounted upon the intermediate portions of the U-shaped members, and means at one end of the scooping mechanism to engage the free ends of the legs of the U-shaped members for causing upward swinging movement of the scoops to a position above the sifting mechanism. 75

5. In a sand handling device for metal foundries, a sifting mechanism, and scooping mechanism to deliver unsifted sand to said sifting mechanism, said scooping mechanism comprising a pair of spaced parallel endless chains connected at intervals by transverse rods, substantially U-shaped members having legs with portions extending at an angle to each other and with the intermediate portions of the legs pivotally engaged with said rods whereby the U-shaped members are mounted for vertical swinging movement, scoops pivotally mounted upon the intermediate portions of the U-shaped members, means at one end of the scooping mechanism to engage the free ends of the legs of the U-shaped members for causing upward swinging movement of the scoops to a position above the sifting mechanism, 80

means to cause travelling movement of said chains, and cooperating lugs for causing tilting of the scoops after the latter are raised for dumping the contents of the scoops. 85

6. In a sand handling device for metal foundries, a sifting mechanism, and scooping mechanism to deliver unsifted sand to said sifting mechanism, said scooping mechanism comprising a pair of spaced parallel endless chains connected at intervals by transverse rods, substantially U-shaped members having legs with portions extending at an angle to each other and with the intermediate portions of the legs pivotally engaged with said rods whereby the U-shaped members are mounted for vertical swinging movement, scoops pivotally mounted upon the intermediate portions of the U-shaped members, means at one end of the scooping mechanism to engage the free ends of the legs of the U-shaped members for causing upward swinging movement of the scoops to a position above the sifting mechanism, 90

means to cause travelling movement of said chains, and cooperating lugs for causing tilting of the scoops after the latter are raised for dumping the contents of the scoops. 95

100

105

110

115

120

ends of the legs of the U-shaped members for causing upward swinging movement of the scoops to a position above the sifting mechanism, means to cause travelling movement of said chains, and cooperating lugs for causing tilting of the scoops after the latter are raised for dumping the contents of the scoops and a frame, said lugs being carried in cooperative relation by the frame and said scoops.

7. In a sand handling device for metal foundries, a sifting mechanism, and scooping mechanism to deliver unsifted sand to said sifting mechanism, said scooping mechanism comprising a pair of spaced parallel endless chains connected at intervals by transverse rods, substantially U-shaped members having legs with portions extending at an angle to each other and with the intermediate portions of the legs pivotally engaged with said rods whereby the U-shaped members are mounted for vertical swinging movement, scoops pivotally mounted upon the intermediate portions of the

U-shaped members, means at one end of the scooping mechanism to engage the free ends of the legs of the U-shaped members for causing upward swinging movement of the scoops to a position above the sifting mechanism, means to cause travelling movement of said chains, and cooperating lugs for causing tilting of the scoops after the latter are raised for dumping the contents of the scoops and a frame, said lugs being carried in cooperative relation by the frame and said scoops, track members arranged to be engaged by the free ends of the legs of the U-shaped members for limiting the upward swinging movement of the scoops to a position wherein the latter are located forwardly of the rods, said scoops being arranged to engage the surface from which the sand is scooped thereby when the scoops are positioned in their normal relation slightly behind and below said rods.

In testimony whereof I affix my signature.

JOSEPH GRUNT.
